UNITED STATES PATENT OFFICE

2,115,770

INDICATOR DEVICE

Oliver R. Hartzell, San Rafael, Calif.

Application August 16, 1937, Serial No. 159,217

3 Claims. (Cl. 40—97)

This invention relates to indicator devices.

An object of the invention is to provide an indicator device which is particularly adapted for use as a score board so as to be easily operated to indicate the score in such a manner that the identical score indication is simultaneously visible on the opposite sides of the indicator device. The same principle may be employed in connection with clocks or the like wherein it is desirable to expose to view identical indications in opposite directions simultaneously.

My invention pertains to improvements related to the type of indicator devices disclosed in my Patent No. 2,057,719, issued on October 20, 1936, for Indicator board, and also in my copending application for Display board Serial No. 21,083, filed May 13, 1936.

Another object of this invention is to provide an indicator device which is highly useful and simple in construction. Convenience of arrangement, lightness and comparative inexpensive of manufacture are further objects which have been borne in mind in the production and development of the invention.

It will be understood that various changes in the details of construction may be made without departing from the spirit or scope of the invention as defined by the appended claims.

With the foregoing and other objects in view, which will be made manifest in the following detailed description and specifically pointed out in the appended claims, reference is had to the accompanying drawings for the illustrative embodiment of the invention, wherein:

Figure 1 is a perspective view of my device.

Figure 2 is a detail view of one face of a panel of my device.

Figure 3 is a detail view of the reverse face of the next following panel of my device.

Figure 4 is a fragmental sectional view of my device.

Figure 5 is a face view of a modified form of my indicator device, with the cover partly broken away.

Figure 6 is a fragmental view of the panels and conveyor of my modified indicator device.

Figure 7 is a detail view of a panel of my modified device, showing one face of the panel; and

Figure 8 is a detail view of the same showing the other face of the panel.

In its general organization the preferred form of my invention consists of a plurality of panels in overlapping position on a conveyor so as to turn over the panels one by one from one side of

the conveyor to the other side. The overlying faces of adjacent panels bear identical markings so that when a panel is turned over it bears on its exposed face the same indicia as that on the uncovered face of the next succeeding panel. Thus the same indication or score is simultaneously exhibited on both sides of the conveyor and in opposite directions to each other. In a score board the pairs of identical numerals are in consecutive series on the superimposed faces of a series of pairs of panels. Each panel therefore is paired with a preceding panel as to one numeral, and is paired with the next succeeding panel as to the next consecutive numeral of a series. The whole series of overlapping panels are moved intermittently by manipulation of the conveyor so as to turn the panels over one by one.

In carrying out my invention in the illustrative embodiment herein I make use of a frame which has a base 11 and three upright posts 12. Each post 12 has a longitudinal cavity 13 at its top portion. In each space on each side of the center post is a score board device for indicating the score of the opposing teams in a game.

The two score board devices are identical, therefore description of one will suffice. An idler roller 14 has its reduced ends 16 extended through elongated slots near the top of the respective posts 12. Each slot is located on the inner side of the post 12 and communicates with the cavity 13. A journal block 18 is slidably disposed in each cavity 13 and rests on a tension spring 19 whereby it is urged upwardly toward the top of the post 12. Each reduced end 16 of each roller 14 is journaled in one of said journal blocks 18. Spaced below the idler roller and parallel therewith is another roller 21 journaled between the posts 12. A reduced end 22 of this roller 21 is extended through the outer post 12 and is provided with a knob 23 whereby the roller 21 may be turned. Over these rollers is extended a belt conveyor 24 of such length that it is held suitably taut by the upward force exerted by the springs 19 on the upper roller 14.

It is to be noted that the upper roller 14 is of much smaller diameter than the lower roller 21 so as to provide a suitable downward and outward incline on both sides of the device. On the conveyor 24 are secured a plurality of indicator panels 26 so that each panel hangs by its upper edge and overlaps partly a plurality of follower panels. In this manner a large number of indications can be achieved in a comparatively small space. In the herein illustration two

flexible hinge flaps 27 are provided at the upper edge of each panel 26 so secured to the conveyor 24 that each panel turns and falls over when carried around the top roller 14 from one side of the device to the other. The upper roller 14 is so proportioned that one half of its circumference is substantially equal to the spacing between the secured edges of adjacent panels. Thus a panel at the top on each side of the device can be exposed to view. The consecutive panels are so marked that both exposed panels 26 at the top indicate the same score.

The panels are so marked that the superimposed faces of the adjacent panels bear the same indicia, in other words consecutive markings appear in pairs on adjacent faces of consecutive panels so that when these adjacent faces are separated and exposed to view on the opposite sides at the top of the conveyor the indication is identical to spectators on opposite sides of the device. Such consecutive panels are shown in Figures 2 and 3. On the panel 26a one face bears the numeral "11" but the other face bears the preceding number "10". On the panel 26b one face bears the numeral "11", and the other face bears the following consecutive numeral "12". The panels 26a and 26b are so placed on the conveyor 24 that the panel 26a precedes the panel 26b for instance in contraclockwise direction viewing Fig. 1 and so that the faces of the panels 26a and 26b which bear the same indicia namely the numeral "11" are superimposed facing each other in all positions except when separated by the top roller 14. Hence each pair of adjacent panels on its combined four faces bears three consecutive numerals, one numeral, for instance "10", on the leading face of the first panel 26a, the next consecutive numeral, in this illustration "11", on both the trailing face of the first panel 26a and also on the adjacent leading face of the next panel 26b, and the next consecutive numeral, namely "12" in this illustration, on the trailing face of the second panel 26b.

In operation each set of panels is used for one of the teams. The scoreboard is so set up near an official that its opposite sides face toward the opposite stands or benches of the spectators. The official turns the device by means of the knob 23 as the respective teams score so as to bring into view the suitable numerals at the top of the conveyor.

In the modified embodiment of my device each panel 31 bears the same numeral or indicia on both sides. The panels 31 do not hang flat with their face toward the conveyor as in the first described embodiment but extend substantially at right angles away from the conveyor chains 32. Each panel 31 is connected to the conveyor chain 32 by means of a yoke 33 fixed to spaced links of the conveyor 32. Each panel 31 is placed into a yoke 33 and is held therein by a pin 34. The yoke 33 is comparatively small and is located near a leading corner of each panel 31 so that the inner or bottom edge of each panel 31 rests against the bottom of a yoke 33 as it is carried around with the conveyor 32.

Two or more such indicator units may be com-

bined, and in this modified embodiment they are inclosed in a casing 36 which has windows 37 near the top aligned with the upright position of the panels 31 on the top of the conveyor turn. There are corresponding windows also on the other side of the casing 36 aligned with the windows 37. The conveyor 32 may be manipulated by means of cranks 38 or the like indicated in broken lines in Fig. 5, or by a transmission 39 from a motor 41 or the like, which may drive one of said units, and, for instance in clock mechanisms the units may be connected to each other for intermittent driving movement by means described in detail in my said copending application.

Having thus described my invention, what I now claim and desire to secure by Letters Patent is:

1. In a display board of the character described a series of indicator panels, means to carry said panels in overlapping relation to each other so as to separate and turn each panel over at a point of its travel so as to successively expose to view the opposite faces of the panel in opposite directions, the overlying faces of adjacent panels of said series bearing the same score indicia so that the exposed face of an overturned panel indicates the same score indicia as the uncovered face of the next panel from which the first panel was overturned, and means for intermittently operating said carrying means at will.

2. A score board comprising a conveyor, a plurality of overlapping panels suspended on the conveyor so as to be turned over one by one at a turn of the conveyor from one side to the other side of said conveyor as the conveyor is moved, thereby to expose to view a face of a panel on each side of the conveyor in opposite directions, each panel bearing consecutive score markings on its opposite faces, and the score markings of the overlying adjacent faces of adjacent panels of said series being the same so that when a panel is overturned it bears on its exposed face the same score marking as that on the uncovered face of the next succeeding panel, and means for moving said conveyor at will.

3. In a display board of the character described a series of indicator panels, means to carry said panels in overlapping relation to each other, means to operate the said panel carrying means, the said panel carrying means consisting of an upper roller, a lower roller and a conveyor spaced around the said upper and lower rollers, one half the circumference of the upper roller being equal to the spacing between the edges of adjacent panels so that as the panel carrying means is moved by the said operating means one of the said panels is turned approximately 360 degrees at a point of its travel so as to successively expose to view the opposite face of the panel in the opposite direction, the overlying faces of adjacent panels of said series bearing the same score indicia so that the exposed face of an overturned panel indicates the same score indicia as the uncovered face of the next panel from which the first panel was overturned.

OLIVER R. HARTZELL.
